(57) **CLAIM**

The ornamental design for a power supply housing, as shown and described.

DESCRIPTION

FIG. 1 is a front left perspective view of a power supply housing having the inventive design;

FIG. 2 is a front right perspective top view of the power supply housing shown in FIG. 1;

FIG. 3 is a bottom right perspective view of the power supply housing shown in FIG. 1;

FIG. 4 is a bottom left perspective view of the power supply housing shown in FIG. 1;

FIG. 5 is a top side view of the power supply housing shown in FIG. 1;

FIG. 6 is a bottom view of the power supply housing shown in FIG. 1;

FIG. 7 is a front view of the power supply housing shown in FIG. 1;

FIG. 8 is a rear view of the power supply housing shown in FIG. 1;

FIG. 9 is an inverted right side view of the power supply housing shown in FIG. 1; and,

FIG. 10 is a left side view of the power supply housing shown in FIG. 1.
